HIGHWAY MARKER WITH REPLACEABLE COVER

Earl E. White, Goldendale, Wash.

Filed Apr. 7, 1959, Ser. No. 804,610

3 Claims. (Cl. 116—63)

The present invention relates to highway traffic markers and more particularly to a highway traffic marker having a replaceable cover.

A very popular type of temporary highway marker is the conical type having a relatively wide base so that it may rest securely on the ground. Such markers are generally painted a bright yellow and lettered with the word slow or other warning to motorists. Used generally in construction zones and other places where traffic is diverted into narrow lanes, they are frequently struck by passing vehicles and this and the frequent handling in positioning the cones tends to dirty or mark the surface of the cones so that they become less visible. Also, the painted surface of such cones weathers in time and loses its brilliance as a warning sign. Heretofore, it has been the practice to repaint a cone that has become damaged or its paint lost its brilliance. However, such painting is expensive not only from the actual labor involved, but also because it requires that cones be taken out of service requiring an extra supply of cones to be maintained so as to have a sufficient number available for use.

It is an object of the present invention to provide a replaceable covering for safety cones. More particularly, it is an object to provide an inexpensive, replaceable cover for conical highway markers.

Other objects and advantages of the invention will become more apparent hereinafter.

In accordance with the illustrated embodiment, the present invention comprises a conical highway marker having a frusto-conical removable covering which can be slipped easily over the narrow end of the marker to mount or remove the covering as desired. The covering can simply and easily be replaced whenever it becomes dirty or it is desired to mount coverings of particular markings upon the marker.

For a more detailed description of the invention, reference is made to the accompanying drawings and following detailed description thereof.

In the drawings:

Fig. 1 is a perspective view of a highway marker of the invention;

Fig. 2 is a perspective view of the covering removed from the marker; and

Fig. 3 is a plan view showing how a sheet may be cut preparatory to forming a frusto-conical configuration desired for the covering.

As shown in the drawings, a highway marker device of the invention comprises a conically shaped, thin walled body designated generally by the numeral 10 mounted upon a relative wide base member 12. The body 10 and the base 12 may be made of any suitable material but may be conveniently formed of molded rubber or other resilient material so that the marker will resist damage if struck by passing vehicles or other objects.

In accordance with the invention, the body 10 is provided with a replaceable covering in the form of a frusto-conical sleeve 14 which is dimensioned so that it seats snugly upon the body 10 intermediate the top thereof

2

and the base 12. In other words, the sleeve 14 is formed so that its diameter at the top is greater than the diameter at the top of the body 10 and with the diameter at the bottom of the sleeve being less than the diameter of the body 10 adjacent the base 12. The sleeve 14 may be of any suitable material, such as paper, parchment, plastic coated paper, or plastic per se. The main requisite is that the covering material be resistant to weathering but inexpensive so that it can be replaced easily.

10 The covering should also be of a material which can be printed or otherwise inexpensively colored with the conventional yellow warning color or other color as desired.

Conveniently, the covering 14 may be formed of sheet material and referring to Fig. 3, a covering may be pre-cut in the shape of the sheet 16 therein shown with opposite edge portions 18 and 20 which may overlap when the sheet is wrapped about the body 10. The portions 18 and 20 may be coated with a contact adhesive so that the coverings may be supplied in flat sheets and wrapped about the body 10 when they are being applied thereto and the portions 20, 18 simply brought into contact and pressed to secure their engagement. Alternatively, the coverings 14 may be formed in their finished frusto-conical shape and stacked and supplied in that fashion.

25 If desired, the covering 14 may be secured to the body 10 by strips of masking tape 22 or other temporary fastening means.

As will be obvious, the coverings can be easily and quickly replaced should they be damaged or marked in any way, thus decreasing the hazard that might exist by a dirty safety marker that could not be easily observed. The use of replaceable coverings will minimize the repainting of the cones and make it possible for such repainting to be deferred until periods when employees 35 are free of other duties.

Having illustrated and described a preferred embodiment of the invention, it should be apparent to those skilled in the art that the invention permits of modification in arrangement and detail. I claim as my invention 40 all such modifications as come within the true spirit and scope of the appended claims.

I claim:

1. A traffic marker comprising a conically tapered body of predetermined height and having a small top and a wide base and a replaceable covering therefor comprising a frusto-conical sleeve having a height less than that of said body and snugly seated upon said body intermediate of said top and said base.

45 2. A traffic marker comprising a conically tapered body of predetermined height having a small top and a wide base and a removable cover on said body comprising a frusto-conical sleeve having the same degree of taper as said body, the diameter of the wide end of said sleeve being less than that of said body base and the diameter of the narrow end of said sleeve being greater than that of said body top so that said sleeve seats snugly upon said body medially of said body.

50 3. A removable cover for a traffic marker comprising a conically tapered body of predetermined height having a small top and a wide base, said cover comprising a frusto-conical sleeve of paper or like sheet material having the same degree of taper as said body, the diameter of the wide end of said sleeve being less than that of said body base and the diameter of the narrow end of said sleeve being greater than that of said body top so that said sleeve may be seated snugly upon said body medially of said body.
